DESIGN FOR A MOISTURE METER

Charles N. Kimball, Johnson County, Kans.,
William R. Lewis, Clay County, Mo., and Herman A. Strecker, Wyandotte County, Kans., assignors to C. J. Patterson Company, Kansas City, Mo., a corporation of Missouri

Application May 17, 1947, Serial No. 139,098

Term of patent 14 years

(Cl. D52—1)

To all whom it may concern:

Be it known that we, Charles N. Kimball, William R. Lewis, and Herman A. Strecker, citizens of the United States, residing in Johnson County, State of Kansas; Clay County, State of Missouri; and Wyandotte County, State of Kansas, respectively, have invented a new, original, and ornamental Design for a Moisture Meter, of which the following is a specification, reference being had to the accompanying drawing, forming part thereof, in which

Fig. 1 of the drawing is a perspective view of a moisture meter, showing our new design,

Fig. 2 of the drawing is a front elevational view of the moisture meter,

Fig. 3 of the drawing is a side elevational view of the moisture meter, and

Fig. 4 of the drawing is a plan view of the moisture meter.

We claim:

The ornamental design for a moisture meter, substantially as shown.

CHARLES N. KIMBALL.
